UNITED STATES PATENT OFFICE.

SAMUEL M. COFFMAN, OF KANSAS CITY, MISSOURI, ASSIGNOR, BY MESNE ASSIGNMENTS, TO OLD WORLD PARFUM COMPANY, OF KANSAS CITY, MISSOURI, A CORPORATION OF MISSOURI.

PERFUME-VENDING MACHINE.

Application filed November 9, 1925. Serial No. 67,943.

This invention relates to coin-controlled perfume discharging machines of that class in which the deposit of a coin of proper size enables the depositor to operate the machine and effect the discharge of a small quantity of liquid perfume in atomized condition upon a handkerchief or the like properly held or disposed to receive such discharge, and my object is to produce an efficient machine of this character of simple, strong, durable and relatively inexpensive construction.

With this general object in view, the invention consists in certain novel features of construction and combinations of parts as hereinafter described and claimed; and in order that it may be fully understood, reference is to be had to the accompanying drawings, in which:

20 Figure 1 is a front view of the operative mechanism of a machine embodying the invention, the cabinet or housing for the mechanism being omitted as it may be of any convenient or preferred type.

25 Figure 2 is a side elevation of the machine as disclosed by Figure 1.

Figure 3 is a vertical section taken on the line III—III of Figure 1.

Figure 4 is a plan view.

30 Figure 5 is a section on the line V—V of Figure 1.

Figure 6 is a section on the line VI—VI of Figure 1.

Figure 7 is a section on the line VII—VII of Figure 6.

Referring to the drawings in detail, 1 indicates a support for the operative mechanism, said support being preferably in the form of a suitable cabinet into which the 40 coins drop and are retained until withdrawn by an authorized person. A vertical cylinder 2 is secured upon the support and provided with a top closure or cap 3, and rising from said cap, at one side of the axial center thereof is a standard 4 in which is mounted at one end a stationary shaft 5. The shaft where it extends through the standard is threaded, and to anchor it securely has an enlargement 6 to bear against one side of the 45 standard and a nut 6^a upon the shaft, bears against the opposite side of the standard.

Arranged vertically is a forked bar 7, guided on enlargement 6 and provided with a stem 8 extending through the cap 3, and

provided at its lower end with a piston or 55 plunger 9 within the cylinder, a coil spring 10 fitting around said stem and exerting force against the cap and piston for the purpose of holding the forked bar yieldingly depressed to its fullest extent, as shown 60 clearly by Figure 3. The piston has a valve seat orifice 11 engaged by a ball valve 12 seated under the pressure of a spring 13 carried by the piston, the arrangement being such that upward movement of the piston 65 results in the unseating of the valve under the air pressure developed, to permit air to pass through the orifice to the lower end of the cylinder, so that when the piston is moved downward and the valve is therefore 70 seated, air will be forced from the cylinder through an opening 14 thereof, for a purpose which hereinafter appears.

Projecting upward and rigid with the cap 3 is a post 15 having an upward arcuate 75 extension 16 grooved at its inner side as at 17, and in the vertical plane of the groove 17 is a coin tube comprising a downward and rearward sloping section 18 and a vertical depending section 19 for discharging the 80 coins into the cabinet through the support 1.

The shaft 5 is disposed axially with respect to the arcuate post extension 16, and journaled on said shaft is a peripherally grooved wheel 21 provided at diametrically 85 opposite points with peripheral coin pockets 22. Said wheel is also provided with a pair of diametrically opposite rollers 23 for alternate engagement with a crosshead 24 secured rigidly to the plunger bar 7, so that twice 90 in each revolution of said wheel the plunger is raised, the spring 10 depressing it immediately upon its release by each of said rollers.

To rotate the grooved wheel a large gear 95 wheel 25 is also mounted in journaled relation to said wheel on shaft 5. The gear wheel is prevented from back rotation by a gravity pawl 25^a suitably mounted on a bracket 25^b carried by the standard 4. 100 Wheel 25 meshes with a gear pinion 26 journaled on a stub shaft 27 secured to a lug 28 projecting from standard 4. A disk clutch member 29 is rotatable with the pinion and is provided with a plurality of ratchet-shaped peripheral notches 30. A flanged disk 31 fits over the disk 29, and in conjunction with said disk and rollers 32 en-

gaging the notches 30, constitutes a clutch. The clutch member 31 is rigid with a shaft 33 journaled on shaft 27 and provided with an actuating handle 34. The handle, together with clutch member 31, may be turned in one direction inoperatively, but when turned in the reverse direction, that is as indicated by the arrow in Figure 2, adjacent to the disk, will impart rotation to clutch member 29 and to the gear wheels 26 and 25, unless one of the pockets of wheel 21 contains a coin against which bears one of a pair of pins 35 projecting from the gear wheel 25, as will be readily seen by reference to Figure 5.

When the machine is at rest, it stands with wheel 21 in the position shown by Figure 5, so that its uppermost pocket shall be just below the lower end of a coin feed tube 36, whose upper end will be accessible for the reception of a coin, which coin will drop down in said tube until arrested by a pin 37 entering said tube through a slot 38 thereof, the pin 37 being carried at the upper end 20 of a pivoted catch 39 mounted on a lug 40 projecting from the cap 3. After the coin is thus arrested, the operator through the actuating handle 34, imparts rotation to the gear wheel 25. The first result of this operation is to cause one of a pair of pins 41, projecting from the gear wheel 25, to press catch bar 39 rearwardly and thus withdraw its pin 37 from the path of downward movement of the coin to permit the latter to drop 30 into the underlying pocket of wheel 21. As this occurs, the adjacent pin 35 of wheel 25, engages the coin and thereby imparts rotation to wheel 21, as indicated by the arrow in Figure 5. During a part of this movement, the coin is guarded against displacement from the pocket by the post extension 18, and just before a half revolution is completed the coin drops into the coin tube section 18 and down through the section 19 until arrested by a pin 43 projecting from a pivoted catch 44, a spring 45 connected to the lever and a bar 46 carried by plunger bar 7, normally holding the catch with its pin 43 in the path of downward movement 45 of the coin. With a slotted or open coin tube as shown, the detention of the coin in section 19 will enable a person to see whether the coin which was instrumental in the operation of the machine is spurious or not.

Pivottally carried by the crosshead 24 is a link 47 connected to the actuating arm 48 of a counter device 49 mounted with coin tube 36, on an arm 50 projecting from standard 4. It will thus be seen that with each upward movement, for example, of the crosshead, the counting device is operated, and with each downward movement of the crosshead the arm 48 is set for the next counting operation.

A pawl 51 pivotally pendent from the

cross-head is disposed with its upwardly-facing tooth 52 adjacent to the face of an intermittently movable disk 53, the disk having in this instance, four pins 54 disposed at equal distances apart and adapted to be 70 successively engaged by the pawl 51, the arrangement being such that with each upward movement of the pawl the disk 53, is turned a quarter revolution, and that upon the downward movement of the crosshead and pawl, the latter is operatively disposed with relation to one of the pins 54, for the next turning movement of disk 53. The function of disk 53 is hereinafter explained, it being understood in this connection that the 80 rollers 23 carried by disk 21, successively engage and elevate the crosshead, and that as each of such rollers passes over center with respect to the axis of disk 21, the tensioned spring 10 is free to effect the instant 85 and rapid descent of the cross head. In such descent the crosshead presses downwardly on the roller 23 which raised it, and thereby continues and accelerates the rotation of disk 21 until the other roller has 90 attained a position in the same horizontal plane as the descending roller, and is engaged by the crosshead, which is therefore arrested as it attains its normal or depressed position. It will be understood that from 95 the time an actuating roller 23 passes rearwardly over center, it is immaterial whether the operator of crank handle 34 continues such operation or not, as from such time, the balance of the half revolution described by 100 disk 21 occurs automatically and cannot be prevented by the operator because the disk 21 bears a journaled relation with respect to the gear wheel 25 and hence to the handle 34.

Secured rigidly to the cap 3 is a plate or arm 55 provided with a shouldered opening 56 for receiving the reduced lower end of and supporting a post 57, a set screw 58 being mounted in plate or arm 55 and adapted 110 to impinge on the post to retain the same in fixed position.

The post constitutes a valve casing 59 for a horizontal tapered valve 60 provided with a stem 61 upon which the disk 53 is rigidly mounted. The valve is also provided with a second stem 62 on which is mounted an expansion coiled spring 63, which bears at one end against a washer 64 fitting loosely on stem 62 and engaging the valve casing, 120 and at its other end against a similar washer 65 fitting on the valve stem 62 and held thereon against outward movement by cross pin 66 secured in the said stem. It will thus be seen, to refer particularly to Figure 6, 125 that the function of the spring 63 is to hold the tapered valve snugly fitted in the casing, and that the function of the disk 53 is to intermittently rotate said valve in quarter-revolution steps.

The valve is provided with a pair of ports 66^a and 67 extending at right angles to each other, and the casing is provided with a pair of feed ports 68 and 69 and a pair of discharge ports 70 and 71. The feed ports 68 and 69 are adapted to respectively communicate alternately with the ports 66^a and 67, and the discharge ports 70 and 71 are adapted likewise to communicate alternately with the ports 66^a and 67, it being noted that when port 67 establishes communication between ports 69 and 71, port 66^a is out of communication with ports 68 and 70, but that when the valve is turned a quarter revolution this arrangement is reversed.

The outer ends of ports 68 and 69 communicate with a tubular coupling 72 connected by a flexible tube 73 with a tubular coupling 74 in communication with discharge port 14 of the cylinder, and the outer ends of casing ports 70 and 71 communicate with a forwardly-projecting discharge nozzle 75 suitably secured to the casing 59.

The valve casing also has a pair of ports 76 and 77 extending upwardly and adapted for communication respectively but alternately with valve ports 66^a and 67. The valve casing is also provided with an upward tubular extension 78 upon which fits a sealing tube 79 of rubber or the like, for engagement by the neck of an inverted bottle or holder 80 containing liquid perfume. A yoke 81 fits over the holder and is secured to opposite sides of the valve casing, and a set screw 82 mounted in the upper end of the yoke, bears upon the bottle or holder to secure it firmly or reliably in position.

As the detailed operation through the instrumentality of a coin has been explained, it will be apparent that with the valve in the position indicated by Figures 6 and 7, the at that time vertical port 66^a, is charged with liquid from the holder. Now as the valve is turned a quarter revolution through the upward movement imparted to the cross-head by one of the wheel-carried rollers 53 as explained, the charged port 66^a is withdrawn from communication with port 76 and the holder and establishes communication between ports 68 and 70. As that relation is established, the crosshead-actuating roller passes over center, and the reaction of spring 10 snaps the crosshead and piston downward, and the piston discharges air forcibly from the lower end of the cylinder through the tube 73, and port 68, this air jet driving the charge of liquid forwardly from port 66^a through port 70 and the nozzle 75, and from the latter it emerges in atomized condition for the purpose of scenting a handerchief or the like disposed adjacent the discharge end of the nozzle. The operation described, at the same time disposes the port 67 vertically and in communication

with charging port 77, so that upon the next 65 quarter revolution of disk 53, a similar discharge from port 67 through port 71 and the nozzle, for scenting purposes, is accomplished.

It will be apparent that with each upward 70 movement of the crosshead, arm 46 carries catch 44 upward, the lower end of the latter in such movement, moving forward under the resistance of the coin in coin tube section 19 and under the inclined wall or edge 75 of notch 19^a, so that said coin can drop into the cabinet, but it will be understood that as the crosshead snaps downward, the catch 44 returns to its initial position as shown by Figure 2, in time to intercept the 80 actuating coin and arrest the same so that it may be under observation in tube section 19, as hereinbefore explained.

From the above description, it will be apparent that I have produced a device of 85 the character described which possesses all of the features of advantage set forth as desirable, and while I have described and claimed the preferred embodiment of the 90 same, I reserve the right to make all changes properly falling within the spirit and scope of the appended claims.

What I claim is:

1. In a machine of the character described, 95 a valve casing having an upright port, an inverted air-tight liquid-container clamped on the casing in communication with said port, the casing also having an air-supply port disposed angularly with respect to the liquid-supply port and a discharge port, a 100 rotatable valve mounted in the casing and provided with a pair of independent diametric ports angularly-disposed relatively to each other for alternately establishing communication with the liquid-supply port and between the air-supply port and discharge port, means for rotating the valve to effect the adjustments mentioned, and means for supplying air under pressure to the air-supply port after each rotary adjustment of 105 the valve to effect the discharge in atomized condition, of the liquid contained in the valve port, at such time, in communication with the discharge port.

2. In a machine of the character described, 115 a valve casing having an upright port, an inverted liquid-container clamped on the casing in communication with said port, the casing also having an air-supply port disposed angularly with respect to the liquid-supply port and a discharge port, a rotatable valve mounted in the casing and provided with a pair of independent angularly-disposed diametric ports, each for alternately establishing communication with the liquid-supply port and between the air-supply port and discharge port, manually-operable 120 means for turning said valve to move one 125

- of the valve ports out of communication with the liquid-supply port and the other valve port into communication with said liquid-supply port and the last-named valve port out of communication with the air-supply port and discharge port and the first-named valve port into communication with the air-supply port and discharge port, and automatic means for supplying air under pressure to the air-supply port after such adjustment of the valve is effected.
3. In a machine of the character described, a valve casing having a liquid-supply port and air-supply and discharge ports, a liquid holder in communication with the liquid-supply port, a rotatable valve having a pair of independent ports for simultaneous communication respectively with the liquid-supply port and with the air-supply and discharge ports, an air cylinder in communication with the air-supply port, a spring advanced piston in the cylinder, a crosshead movable with the piston, a yieldingly-closed valve mechanism partitioning the cylinder into two non-communicating chambers when the piston is on its compression stroke, a rotatable disk adapted for imparting step by step rotation to the rotatable valve, rotatable supporting means, devices carried by the said rotatable supporting means and engaging the under side of the crosshead and adapted as the rotatable supporting means is turned to retract the crosshead and piston and then release them, means carried by the crosshead and adapted when the latter is retracted to rotate the valve-actuating disk one step.
4. In a machine of the character described, a valve casing having a liquid-supply port and air-supply and discharge ports, a liquid holder in communication with the liquid supply port, a rotatable valve having a pair of independent ports for simultaneous communication respectively with the liquid-supply port and the air-supply and discharge ports alternately as the valve is rotated in steps, an air cylinder in communication with the air supply port, a piston in said cylinder, a yieldingly-closed valve mechanism partitioning the cylinder into two non-communicating chambers when the piston is on its compression stroke, a crosshead and means connecting the crosshead to the piston, a rotatable disk, means carried by the disk and engaging the under side of the crosshead and adapted as the disk is turned to raise the crosshead and then release it, a second rotatable disk connected to said rotatable valve, actuating means carried by the crosshead and adapted when the latter is retracted to engage means carried by said second rotatable disk to rotate said rotatable valve one step, means to effect the return of the crosshead and the piston to their original positions when the former is released, and yielding means for arresting the rotat-

able valve after each step of rotation of the same.

5. In a machine of the character described, a valve casing having a liquid-supply port and air-supply and discharge ports, a liquid holder in communication with the liquid-supply port, a rotatable valve having a pair of independent ports for simultaneous communication respectively with the liquid-supply port and the air-supply and discharge ports alternately as the valve is rotated in steps, an air cylinder in communication with the air-supply port, a piston, a crosshead connected to said piston, a yieldingly-closed valve mechanism partitioning the cylinder into two non-communicating chambers when the piston is on its compression stroke, a rotatable disk, means carried by the disk and engaging the advance side of the crosshead and adapted as the disk is turned to raise the crosshead and then release it, means for advancing the crosshead when released, means carried by the crosshead and adapted when the latter is retracted to rotate the ported valve one step, means to effect the return of the crosshead and the valve-operating means to their original positions when the former is released, and a counting mechanism operating with each ported valve-actuating movement.

6. In a machine of the character described, a reciprocating crosshead, a cylinder having an air discharge port, a piston in the cylinder, a yieldingly-closed valve mechanism completely partitioning the cylinder between said port and the piston except when the latter is on its compression stroke, said crosshead being movable with the piston, a rotatable disk, a pair of diametrically opposite devices carried by the disk, said devices being normally in engagement with the advance side of the crosshead and for alternately applying pressure on the latter to retract the same and the piston when the disk is turned a predetermined distance, and means for automatically reversing the operation of the piston and crosshead to force air from the cylinder and cause the crosshead by pressure on the disk-carried device which retracted the piston and crosshead, to continue the rotation of the disk until both of said devices are again in contact with the advance side of the crosshead.

7. In a machine of the character described, a valve casing having a liquid-supply port, an air-supply port and a discharge port, an air-tight liquid-holder having communication adjacent its bottom with the liquid-supply port, a valve having a port for charging by the liquid-supply port, means for intermittently supplying air under pressure to said air-supply port, and means for actuating said valve in timed relation to the operation of said air-supply means to close communication of its port with the liquid-

supply port and open communication with its said port and the air-supply and discharge ports.

8. In a machine of the character described, 5 a valve casing having a liquid-supply port, an air-supply port and a discharge port, an air-tight liquid-holder in communication adjacent its bottom with the liquid-supply port, a rotatable valve having a pair of independent ports for simultaneous communication

respectively, with the liquid-supply port and with the air-supply and discharge ports, means for intermittently supplying air under pressure to said air-supply port, and means for actuating said rotatable valve in 15 timed relation to the operation of said air-supply means.

In witness whereof I hereunto affix my signature.

SAMUEL M. COFFMAN.
